(57) **CLAIM**

The ornamental design for a screen for projection, as shown and described.

DESCRIPTION

FIG. 1 is a front view of a screen for projection showing my new design;

FIG. 2 is a rear view thereof;

FIG. 3 is an enlarged left side view thereof;

FIG. 4 is an enlarged right side view thereof;

FIG. 5 is a top plan view thereof;

FIG. 6 is a bottom plan view thereof;

FIG. 7 is a front view thereof, in which a handle is raised;

FIG. 8 is an enlarged right side view thereof, in which a handle is raised;

FIG. 9 is a top plan view thereof, in which the legs are rotated;

FIG. 10 is a front view thereof, in which a screen is extended;

FIG. 11 is a rear view thereof, in which a screen is extended;

FIG. 12 is a right side view thereof, in which a screen is extended;

FIG. 13 is a cross-sectional view taken along the line 13—13 of FIG. 4; and,

FIG. 14 is a cross-sectional view taken along the line 14—14 of FIG. 5.
